UNITED STATES PATENT OFFICE.

GEORGE S. BURR, OF BRECKINRIDGE, COLORADO.

ORE-CONCENTRATOR.

SPECIFICATION forming part of Letters Patent No. 251,828, dated January 3, 1882.

Application filed March 21, 1881. (No model.)

To all whom it may concern:

Be it known that I, GEORGE S. BURR, of Breckinridge, in the county of Summit and State of Colorado, have invented certain new and useful Improvements in Ore-Concentrators, of which the following is a full, clear, and exact description, reference being had to the accompanying drawings, forming part of the same, and in which—

10 Figure 1 is a side elevation of the concentrator; Fig. 2, a longitudinal section, and Fig. 3 an end elevation.

15 My invention relates to ore-concentrators, and has for its object the separation of gangues and other foreign matter from the precious metal, whereby results economy in transporting and reducing the ore and in the yield of the precious metal; and it consists in the construction and combination of means hereinafter 20 particularly described, and then sought to be specifically defined by the claims.

25 In the accompanying drawings, the letter A indicates a revolving cylinder, open at both ends, of the same diameter from end to end or tapering from one end to the other, and provided internally with a spiral blade, B, running from one end to the other of the cylinder, and adapted when the cylinder is revolved to carry what ore may be placed therein from the 30 introducing-point to the discharging-point. The cylinder is held by a strap, C, or other suitable means to a tilting frame, D, the trunnions E of which rest in the posts F of the base G. The cylinder A is provided around 35 its exterior, between its ends, with a circumferential gear, H, which is in mesh with the pinion I on the end of a shaft, J, journaled in the boxes K, which are bolted to the top of one side of frame D. To the other end of this 40 shaft there is suitably secured a bevel-gear, L, which engages with the bevel-gear M on the shaft N, journaled in boxes O (only one of which is shown) and operated by crank P. These gears are for revolving the cylinder A.

45 Any inclination desired can be given to the cylinder by tilting the frame D, which will be held to the inclination by a set-screw, Q, passed into or against the side of the frame through the slotted end of a segment, R, secured at the 50 other end to the post F. Any other suitable means than those described can be used to revolve the cylinder, to tilt the frame and hold

it to its inclination. A pipe, S, perforated so as to direct water against the side of the cylinder and connected with the source of water-supply, is held within the cylinder at one end by an arm, T, extending from one side of the tilting frame D, to which it is bolted, to a point in front of the open end of the cylinder, so as not to interfere with the rotation of the cylinder.

To serve as frictional supports for the cylinder and as guides for the same, and which may also aid in holding the cylinder on the frame by fitting into grooves a formed across the exterior of the cylinder, disks or wheels U are bolted or otherwise secured to the ends of the frame D, so as to bear against the outside of the cylinder, and are preferably journaled so as to turn.

In operation the broken or pulverized ore mixed with gangue and other foreign matter is introduced by means of a chute, V, or other suitable means into the lower end of the cylinder while the latter is being revolved. It is then taken hold of by the spiral blade B and carried to the upper end of the cylinder. While it is progressing from the lower end to the upper end it is subjected to the flow of water introduced into the cylinder at its upper end through the perforated pipe or by other means. The water carries off through the lower end of the cylinder the gangue and other foreign matters, while the spiral blade carries to the top or upper end of the cylinder the heavier or precious metal freed from the foreign matters. The water flows between the spirals and over them from top to bottom; and by the means described the ore is very thoroughly cleansed or separated from the foreign matters.

Having described my invention, what I claim is—

1. An ore-concentrator consisting of a revolving cylinder having a spiral blade connected to its inner circumference, and extending from end to end of the cylinder, in combination with means for tilting the cylinder and holding it to its adjusted position, substantially as set forth.

2. An ore-concentrator consisting of a revolving and tilting cylinder having a spiral blade extending along its inner circumference from one end to the other of the cylinder, in combination with means for locking the cylin-

der to its adjusted position, and a water-supply adjustable with the cylinder, so as to maintain its relative position thereto no matter what the pitch of the cylinder be, substantially as set forth.

3. An ore-concentrator consisting of a revolving cylinder having a spiral blade connected to its inner circumference, and extending from end to end of the cylinder, in combination with the supporting and tilting frame D, segment R, and a set-screw for locking the parts, substantially as set forth.

4. The revolving cylinder provided with a spiral blade within its circumference, in com-

bination with the supporting and tilting frame 15 D and arm T, connected to the frame and extending to a point in front of the cylinder, and supporting the supply-pipe S, whereby the several parts are adapted to operate as set forth.

In testimony that I claim the foregoing as my invention I hereunto affix my signature this 19th day of February, A. D. 1881.

GEORGE S. BURR. [L. S.]
